UNITED STATES PATENT OFFICE

ELIZABETH W. DE HUFF, OF SANTA FE, NEW MEXICO

DESIGN FOR A DOLL

Application filed January 30, 1931. Serial No. 38,484. Term of patent 7 years.

To all whom it may concern:

Be it known that I, ELIZABETH W. DE HUFF, a citizen of the United States, residing in Santa Fe, in the county of Santa Fe and State of New Mexico, have invented a new, original, and ornamental Design for a Doll, for which the following is a specification, reference being had to the accompanying drawing.

I claim:

The ornamental design for a doll, as shown.

ELIZABETH W. DE HUFF.
